UNITED STATES PATENT OFFICE.

HENRY VERNON CARVER, OF GASTONIA, NORTH CAROLINA.

ADJUSTABLE SHUTTLE BINDER FOR LOOMS.

Application filed March 5, 1924. Serial No. 697,097.

To all whom it may concern:

Be it known that I, HENRY V. CARVER, a citizen of the United States, residing at Gastonia, in the county of Gaston and State 5 of North Carolina, have invented a new and useful Adjustable Shuttle Binder for Looms, of which the following is a specification.

This invention relates to an adjustable shuttle binder for looms, which is used for 10 checking the movement of the shuttle as it enters the box at the end of its movement, and for yieldingly holding the same until it is released by the action of the picker. The structure herein disclosed embodies certain features which are disclosed in my 15 earlier application, Serial No. 605,436, filed December 7, 1922, of which the present application is a continuation in part.

In looms as now generally constructed, the 20 shuttle binder is held in operative relation to the shuttle by means of a bow spring, which often breaks and permits the shuttle to bounce out, which not only causes damage to the warp, but in many instances inflicts serious injury on the operator, or any other person who may be in the vicinity.

The object of the present invention, generally stated, is to provide a binder adapted for use either on plain or on automatic looms, which will be simple and inexpensive 25 in its construction, as well as durable and efficient in its operation, and more specifically to provide such a binder which may be readily attached to any lay, and which 30 may be held and adjusted for different shuttles without the use of springs or other structure which is liable to break.

Other minor objects and advantages will 35 be apparent from the following description taken in connection with the accompanying drawing, which illustrates the specific construction of one form in which my invention may be embodied.

In the drawing:

Figure 1 is a front elevation of the end 40 of the lay having my invention applied thereto.

Figure 2 is a plan view thereof.

Figure 3 is a perspective view of the invention detached from the lay. 50

Figure 4 is a horizontal section through the binder and its supporting means.

Figure 5 is a vertical section taken substantially on the line 5—5 of Figure 4. 55

Referring specifically to the drawing, 1 indicates a lay in which the shuttle 2 operates, and which is provided with the usual front mouth piece 3, rear mouth piece 4, and protector rod 5 having an upstanding thumb 6. At the inner end of the shuttle box is 60 the usual picker 7.

In carrying out my invention the usual bracket, which is used in connection with the bow spring shuttle binder, is removed and replaced by a casting 8 of special design, which is secured to the end of the lay by suitable bolts 9, or the like. The casting 65

8 is provided at its upper side with an integral channel shaped bracket 10 having slots 11, which are in vertical registration and extend in a direction transverse to the lay. 70

A pivot bolt 12 is adjustably secured in the slots 11, and form a support about which the shuttle binder 13 may rock. For supporting the binder a metallic plate 14 is secured to its back, preferably by means of 75

bolts 15, whose heads 16 are countersunk in the face of the binder, and the inner end of the plate extends across the end of the binder, as indicated at 17. A sleeve 18 is 80

formed integral with the plate 14 and pivotally receives a bushing 19, which is mounted on the bolt 12. The bushing 19 is slightly longer than the sleeve 18, so that the latter 85

may rock freely thereon. The bushing is provided at one end with an integral head 20, while the other end is reamed out and removably receives the reduced portion 21 of a head or washer 22, whereby the bushing and bolt 12 may be securely held in their 90 adjusted relations to the slots 11. An oil hole 23 may also be provided in the sleeve 18.

The binder 13 may be made of wood or any other suitable material, and is provided with a swell 24 covered with a facing 25, 95 preferably of leather. The binders are

made in standard sizes with the swells cut to fit shuttles of different sizes and lengths. The free end of the binder is provided with a facing 26, preferably of rubber, which is 5 adapted to contact with the protector thumb 6, whereby the necessary rocking movement is imparted to the binder to bring it into operative relation with the shuttle. The binders are cut so that the shuttle will be 10 entirely clear of the warp before the braking action begins.

In order that the binder may be used in connection with an automatic loom, a pair of holes 27 are cut at the proper points to 15 receive the feeler fingers 28 as the filling is beaten up, and a portion of the binder is cut away at the back, as shown at 29, so as to permit the feeler fingers to reach the quill in the shuttle, and to perform their function 20 properly without the frame 30 striking the binder.

As a further insurance against accidents, I have provided a safety stop, which comprises an adjustable screw 31, threaded into 25 the bottom of the channel 10 and secured in its adjusted position by means of a lock nut 32. In case the bolt 12 becomes loosened, permitting the plate 14 which carries the binder to slip outwardly, it is stopped by the 30 sleeve 18 coming in contact with the end of the screw 31, thus preventing the shuttle from bouncing out, or making slack filling in the cloth, or causing other damage to the goods or injury to the operator.

35 From the foregoing description it is to be particularly noted that in the construction of my binder, and the adjustable support therefor, no springs are used, but on the other hand the binder is supported for free 40 rocking movement, which is aided by the contact of the protector thumb 6 with the facing 26 on the free end of the binder. The casting 8 and the channel shaped bracket 10 are made in one integral piece, so shaped 45 that it may be easily secured to the lay in place of the usual bracket which supports the bow spring binder. This provides a very simple and effective support for the binder, which is not likely to break, and 50 which, with the proper size of binder and proper adjustment, may be used in connection with any size or type of shuttle. While the feeler holes 27 and channel 29 are customarily provided, so that the binder may 55 be used in connection with an automatically changed shuttle before all of the filling is run off of the quill, it is to be noted that the same binder may also be used with advantage on a plain loom.

60 For the purpose of illustration, I have shown and described the specific construction of one form in which my invention may be embodied, but it will be understood that various modifications may be made therein 65 within the scope of what is claimed without

departing from the salient features of the invention, or sacrificing any of its advantages.

What is claimed is:

1. In a loom having a shuttle box with a 70 protector rod supported near its mouth and having an upstanding thumb, a bracket having integral spaced arms with opposed slots therein, means for securing the bracket to the side of the shuttle box with the arms 75 one above the other and the slots in vertical registration and disposed in transverse relation to the box, a bolt secured in said slots and adjustable longitudinally thereof, and a binder pivoted to swing freely on said bolt with its free end disposed in the path of the protector thumb.

2. In a loom, the combination of a bracket having integral spaced arms with opposed slots therein, means for securing the bracket to the side of the shuttle box with the arms one above the other and the slots in vertical registration and disposed in transverse relation to the box, a bolt secured in said slots and adjustable longitudinally thereof, 80 a binder pivoted to swing freely on said bolt, and an adjustable stop in said bracket to limit the movement of the shuttle in case said bolt becomes loose, and thereby preventing the shuttle from bouncing out. 95

3. In a loom, a shuttle box, a bracket secured to the side thereof and having integrally formed horizontal arms extending in a direction transverse to the box, a bolt adjustably secured in the arms, and a binder 100 having a metallic strip secured thereto, said strip having its intermediate portion enlarged to form a sleeve which is journaled on said bolt.

4. In a loom, a shuttle box, a bracket secured to the side thereof and having integral slotted horizontal arms extending in a direction transverse to the box and arranged one above the other, a bolt adjustably secured in the slots, and a shuttle binder pivotally supported near one end on said bolt. 105

5. In a loom, the combination of a bracket, means for securing the same to the side of the shuttle box, a vertically disposed bolt mounted in the bracket and adjustable transversely of the shuttle box, a shuttle binder pivoted near one end on said bolt, and an adjustable stop mounted in the bracket in rear of said bolt to engage the binder and prevent the shuttle from bouncing out in the event that the bolt becomes loosened. 115

6. In a loom, the combination of a shuttle binder, a metallic strip secured to the back and one end of the binder and provided with a vertical sleeve, a bolt on which the sleeve is mounted, a bracket having arms in which the bolt is rigidly held, said bolt being adjustable transversely of the box, and means for securing the bracket to the box in such a position that the free end of the binder 125

is in the path of the protector thumb near the mouth of the box.

7. In a loom, the combination of a bracket having integral spaced arms with opposed 5 slots therein, means for securing the bracket to the side of the shuttle box with the arms one above the other and the slots in vertical registration and disposed in transverse relation to the box, a bolt adjustably mounted

in said slots, and a binder pivoted to swing 10 freely on said bolt, said binder being provided with transverse holes so located as to permit the feeler fingers to enter therethrough and reach the quill while the filling is beaten up.

In testimony that I claim the foregoing as my own, I have hereto affixed my signature.

HENRY VERNON CARVER.
